H. G. TRAVER.

FLUSHING APPARATUS AND VALVE MECHANISM THEREFOR.

APPLICATION FILED MAR. 17, 1917.

1,244,922.

Patented Oct. 30, 1917.

INVENTOR:

H. G. Traver

By his Attorney John O. Seifert

UNITED STATES PATENT OFFICE.

HARRY G. TRAVER, OF RIDGEWOOD, NEW JERSEY.

FLUSHING APPARATUS AND VALVE MECHANISM THEREFOR.

1,244,922.

Specification of Letters Patent. Patented Oct. 30, 1917.

Application filed March 17, 1917. Serial No. 155,382.

To all whom it may concern:

Be it known that I, HARRY G. TRAVER, a citizen of the United States, and resident of Ridgewood, in the county of Bergen and State of New Jersey, have invented certain new and useful Improvements in Flushing Apparatus and Valve Mechanism Therefor, of which the following is a specification.

This invention relates to water flushing apparatus particularly adapted for flushing toilet bowls, urinals and the like in which the water for flushing purposes is under abnormal air pressure or greater than ordinary atmospheric pressure, and it is the primary object of the invention to improve and simplify the general construction of flushing apparatus of this character to cheapen the cost of manufacture and at the same time increase the efficiency thereof.

It is a further object of the invention to provide a flushing apparatus in which manually operable means is provided to perform the initial function of opening or unseating a valve to release the flushing water, and in which the incoming water to the reservoir operates to open the valve as it is unseated and with the pressure of the water in the reservoir during the flushing operation maintains the valve open, said incoming water also operating to close the valve after the flushing operation and with the pressure of the water in the reservoir maintain the valve closed.

Another object of the invention relates to improved valve mechanism to control the flow of water from the reservoir and to improved means to actuate the valve.

With the foregoing objects and other objects and advantages hereinafter set forth I have shown in the drawing in side elevation, partly in section, a flushing apparatus illustrating an embodiment of my invention.

The embodiment of my invention shown in the drawing comprises an air tight water reservoir or tank 1, only a portion of said reservoir being shown, from the lower portion of which the water is discharged, as through an opening 2 at the bottom connected to a closet bowl 3 through a pipe 4 connected at one end to the opening in the reservoir and at the other end to the inlet of a valve chamber 5, and a pipe 6 connected at

one end to the outlet of the valve chamber and at the opposite end to the closet bowl 3. 55

The flow of water from the reservoir is controlled by valve mechanism comprising the chamber 5 and a gravity seating valve opening into the valve chamber, or having a closing movement toward and an opening 60 movement away from the outlet of the valve chamber. This valve is in the nature of a flap valve comprising a disk 7 having a stem to engage in an opening in a carrier of slightly larger diameter than the stem by a 65 nut threaded onto the stem whereby the disk may have rotative movement and a slight lateral movement relative to the axis of the stem to permit of the ready seating of the valve. The carrier is pivotally supported 70 at the top of the valve chamber, as at 8, to swing on a horizontal axis. The valve is adapted to coöperate with an annular valve seat 9 at the outlet of the valve chamber, this seat extending in a direction 75 slightly inclined to the perpendicular thereby facilitating the seating of the valve disk. Access may be had to the valve chamber through an opening closed by a removable plug 10. 80

The connection of the water connection pipe 4 with the valve chamber is such as to lead the water into the valve chamber below the valve opposite the pivotal support of the valve and direct the water in a vertical direction transverse to the valve seat and the opening and closing movements of the valve to intersect the path of movement of the valve, for which purpose the pipe 4 is substantially of U-shape as shown. The 90 water inlet connection of the reservoir 1 with a water main is also through the pipe 4 and the opening 2 by a water inlet pipe 11 of less diameter than the pipe 4 and is connected to the pipe 4 adjacent the connection 95 of the pipe 4 with the valve chamber for a purpose to be hereinafter described. To drain the entire water or any sediment from the reservoir and valve chamber there is provided in the pipe 4, preferably in the bend 100 thereof, a drain cock 12. This cock may also be utilized to admit fresh air into the reservoir.

The valve is unseated by a plunger 13 slidably supported in and extending through an 105 opening in the wall of the valve chamber

and a stuffing box 14, and is reciprocable in a direction in line with the valve. The inner end of the plunger is preferably rounded and adapted to engage with an abutment or boss 15 connected to or integral with the valve disk 7, the outer surface of said abutment preferably being rounded to receive the shocks and wear of the plunger and protect the ground face adjacent to the periphery of the valve disk 7. The plunger is manually operable from the exterior of the valve chamber to unseat the valve by a hand lever pivotally supported at 16 having a pin and slot connection 17 with the plunger, and having a weighted hand grip 18 whereby when the lever is manually operated to impart movement to the plunger in one direction or into the valve chamber to unseat the valve and as it is released the weighted end of the lever will drop by gravity and automatically impart return movement to the plunger.

In operation the water from the main enters the reservoir compressing the air therein until the air is compressed to a point when the air pressure on the water is equal to and will overcome the pressure of the water entering from the main through the pipe 11. To perform the operation of flushing the handle is lifted thereby moving the plunger into the valve chamber, the end of the plunger engaging the abutment 15 and moving the valve plate 7 from its seat. As soon as the valve is unseated the water in the pipe 4 due to the pressure of the air in the reservoir 1 and the pressure of the water in the inlet pipe 11 will be forcibly directed in a vertical direction into the valve chamber to intersect the path of movement of the valve and will impinge against the outer face of the valve, or the side of the valve toward the outlet of the valve chamber, operating to lift the valve to the dotted line position adjacent the top of the valve chamber and is maintained in such position so long as the pressure of the water from the reservoir and through the inlet pipe 11 is sufficient to maintain the valve in its raised position. As soon as the air pressure in the reservoir is reduced whereby the pressure of the water on the valve is not sufficient to maintain the valve in its raised position the valve will drop by gravity and as the valve begins to drop the pressure of the flow of water through pipe 11 will be directed against the inner or rear face of the valve and operate to firmly seat the valve, and the valve will be maintained seated by the increasing pressure of the water flowing into the reservoir. After inward movement has been imparted to the plunger to unseat the valve the plunger operating lever is released when it will immediately drop and return the plunger to initial position.

While the pressure of the incoming water

through the pipe 11 into the reservoir must be sufficient to compress the air in the reservoir and provide a sufficient quantity of water therein combined with the water flowing through pipe 11 for flushing purposes, the pressure of such water through pipe 11 must not be so great as to overcome the weight of the valve 7 and thereby prevent said valve from falling to its seat. I therefore provide a valve (shown in a general way at 19) to control the flow and regulate the pressure of the water through said pipe 11.

Having thus described my invention, I claim:

1. In a flushing apparatus, the combination of an air tight reservoir; a valve chamber; a gravity seating valve opening into the valve chamber; manually operable means to unseat said valve; and a connection to the valve chamber from the reservoir leading into the valve chamber below the valve, substantially as and for the purpose specified.

2. In a flushing apparatus, the combination of an air tight reservoir; a valve chamber; a gravity seating valve supported in the valve chamber opening into the valve chamber; a water inlet to the valve chamber from the reservoir leading into the valve chamber below the valve; and manually operable means to unseat the valve; the pressure of the incoming water through the inlet of the valve chamber operating to open the unseated valve and maintain it open during the flushing operation, said valve seating by gravity after the flushing operation and the increasing pressure of the water in the reservoir operating to maintain the valve closed.

3. In a flushing apparatus, the combination of an air tight reservoir; a valve chamber; a gravity seated valve in said chamber opening into the chamber; manually operable means to unseat said valve; and means to connect the valve chamber with the reservoir to lead the water upward into the valve chamber in a vertical direction.

4. In a flushing apparatus, the combination of an air tight reservoir; a valve chamber having an outlet; a valve in the valve chamber opening into the valve chamber to control the flow of water through the valve chamber; manually operable means to open said valve; and an inlet to the valve chamber connected to the reservoir to direct the flow of water upward into the valve chamber in a direction to intersect the path of movement of the valve.

5. In a flushing apparatus, the combination of an air tight reservoir; a valve chamber; a gravity seated valve in said chamber opening into the chamber; a plunger operable from the exterior of the valve chamber to unseat said valve; and means to connect the valve chamber with the reservoir to di-

rect the flow of water into the valve chamber in a vertical direction and to intersect the movement of the valve.

6. In a flushing apparatus, the combination of an air tight reservoir; a valve chamber having an outlet; a gravity seated valve pivotally supported in the valve chamber to close the outlet; a plunger operable from the exterior of the chamber to unseat said valve; and means to connect the valve chamber with the reservoir to direct the flow of water into the valve chamber in a direction to intersect the path of movement of the valve.

7. In a flushing apparatus, the combination of an air tight water reservoir; a valve chamber having an outlet; a flap valve pivotally supported adjacent the top of the valve chamber, said valve opening into the valve chamber and coöperating with a valve seat at the outlet of the valve chamber; means manually operable from the exterior of the valve chamber to unseat the valve; and a water connection to the valve chamber from the reservoir leading into the valve chamber below the pivotal support of the valve, substantially as and for the purpose specified.

8. In a flushing apparatus, the combination of an air tight water reservoir; a valve chamber having an outlet; a flap valve pivotally supported adjacent the top of the valve chamber, said valve opening into the valve chamber and coöperating with a valve seat at the outlet of the valve chamber; a slidably supported plunger; means operable from the exterior of the valve chamber to move said plunger to unseat the valve; an inlet to the valve chamber opposite to the pivotal support of the valve; and a pipe to connect said inlet with the reservoir.

9. In a flushing apparatus, the combination of an air tight water reservoir having an opening at the bottom to serve as the water inlet and outlet; a valve chamber having an inlet to direct the flow of water in a vertical direction into the valve chamber and an outlet; a pipe connected to the reservoir opening and the inlet of the valve chamber; a flap valve to coöperate with a seat at the outlet of the valve chamber pivotally supported adjacent the top of the valve chamber; means operable from the exterior of the valve chamber to unseat said valve; and a water inlet leading into the pipe connecting the valve chamber and reservoir adjacent the connection thereof with the valve chamber, substantially as and for the purpose specified.

10. In a flushing apparatus, the combination of an air tight water reservoir having an opening at the bottom to serve as the water inlet and outlet for the reservoir; a valve chamber having an inlet and an outlet; a substantially U-shaped pipe connected to the reservoir opening and the inlet of the valve chamber to direct the flow of water into the

valve chamber in a vertical direction; a valve seat in the valve chamber at the outlet thereof; a pivotally supported valve opening into the valve chamber to coöperate with the valve seat to close the outlet of the valve chamber; a plunger manually operable from the exterior of the valve chamber to unseat the valve; and a water inlet leading into the U-shaped pipe connecting the reservoir and valve chamber adjacent the connection thereof with the valve chamber, the pressure of the water in the reservoir operating to open the valve as it is unseated and maintain the valve open during the flushing operation, and the valve seating by gravity after the flushing operation and the pressure of the water in the reservoir maintaining the valve closed.

11. In a flushing apparatus, the combination of an air tight water reservoir and a closet bowl connected thereto, of a connection to a water main in the connection of the reservoir and closet bowl; a valve chamber in the connection of the reservoir and closet bowl; a flap valve pivotally supported in the valve chamber opening into the valve chamber; a plunger slidably supported in line with the valve; and means connected to said plunger to manually move the same and thereby unseat the valve, substantially as and for the purpose specified.

12. In flushing apparatus, the combination of an air tight reservoir and a closet bowl, of a valve chamber interposed between the reservoir and bowl; an annular valve seat in said chamber; a gravity seating flap valve to coöperate with said seat; and an inlet to the chamber from the reservoir transverse to the valve seat and the movement of the valve.

13. In flushing apparatus, the combination of an air tight reservoir and a closet bowl, of a valve chamber interposed between the reservoir and bowl; an annular valve seat in said chamber; a flap valve pivotally supported in said chamber to swing on a horizontal axis; and an inlet to the valve chamber opposite to the pivotal support of the valve and transverse to the valve seat.

14. In flushing apparatus, the combination of an air tight reservoir and a closet bowl, of a valve chamber interposed between the reservoir and bowl; an annular valve seat in said chamber extending in a direction to slightly incline to the perpendicular; a flap valve pivotally supported adjacent the top of the chamber to swing on a horizontal axis and coöperate with the valve seat; an inlet to the bottom of the valve chamber to direct the water upward into the chamber in a vertical direction transverse to the valve seat and movement of the valve; a plunger to unseat said valve; and a manually operable lever to move the plunger from the exterior of the chamber.

15. Valve mechanism for flushing apparatus comprising a valve chamber having an outlet; a valve in said chamber having an opening movement away from the outlet; an inlet to the valve chamber to direct the flow of water upward into the valve chamber in a direction to intersect the path of movement of the valve; a plunger to unseat said valve;

and a weighted lever manually operable to impart movement to the plunger to unseat the valve and to automatically impart return movement to the plunger.

Signed at New York city, in the county of New York and State of New York, this 16th day of March, 1917.
